Dec. 1288

Garrison Smith & Henry Brown of Philadelphia Pa.
Assignor to Samuel Smith.
Letters Patent No 1288. Dated July 17 1860.

The schedule referred to in these Letters Patent and making part of the same.

To all whom it may concern:

It is known that we, Garrison Smith and Henry Brown, both of the City of Philadelphia, and State of Pennsylvania, have invented or produced a new and original design for the plates of a Cooking Stove termed the Combination, and we do hereby declare the accompanying drawing and following explanation thereof to form a full clear and exact representation and description of the said design -

Fig: 1. is the said drawing representing one of the side plates with its doors.

Fig: 2. the front plate with its doors.

Fig: 3. the back plate, and

Fig: 4. the leg -

The front plate Fig: 1. is plain and is edged with plain mouldings its doors A. B. and C, having the scroll, foliated, and ribbed ornaments represented in the drawing.

The front plate Fig. 2, with its doors, and the back plate Fig. 3, has ornaments of a character similar to those on the side plates, the leg being ornamented in the style represented in the drawing.

We claim the ornamental figures and forms represented in and by the accompanying drawing, the whole forming an ornamental design for the plates of a Cooking Stove.

In testimony whereof, we have signed our names to this specification in the presence of two subscribing witnesses.

Witnesses.

Asst. Henry Brown,
S.M.P. James McEachen.
